W. K. HOWE.

SYSTEM FOR AUTOMATICALLY CONTROLLING RAILWAY TRAINS.

APPLICATION FILED JULY 27, 1915. RENEWED MAR. 27, 1919.

1,360,750.

Patented Nov. 30, 1920.

UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

SYSTEM FOR AUTOMATICALLY CONTROLLING RAILWAY-TRAINS.

1,360,750.

Specification of Letters Patent.

Patented Nov. 30, 1920.

Application filed July 27, 1915, Serial No. 42,166. Renewed March 27, 1919. Serial No. 285,637.

To all whom it may concern:

Be it known that I, WINTHROP K. HOWE, a citizen of the United States, and a resident of the city of Rochester, in the county of 5 Monroe and State of New York, have invented a new and useful System for Automatically Controlling Railway-Trains, of which the following is a specification.

This invention relates to systems for automatically controlling railway trains, and more particularly to such systems in which the movement of a train is controlled, in some appropriate way, by a control relay carried on the train, the energization or de- 10 energization of said control relay being governed by current supplied to the train in accordance with the traffic conditions as said train passes certain points along the track, said controlling current being preferably 15 transmitted to the vehicle by means of contact shoes coöoperating with ramps or contact rails located at said points.

One of the principal objects of the invention is to devise a system for automatically controlling railway trains of the character specified, which will permit the use 20 of a number of motor cars or locomotives equipped with automatic train control apparatus, and which allows the simultaneous 25 operation of the apparatus on all of said cars or locomotives without impairing the efficiency of the system, and regardless of the number of motor cars or locomotives or 30 their positions in the train, or of the length 35 of the blocks or of the train.

A further object of the invention is to devise a system of automatic train control of the character specified, which prevents undue or improper flow of current in case two or 40 more motor cars or locomotives equipped with the train control apparatus are included in a train and are provided with a continuous electrical conductor between them, the distance between said motor cars 45 or locomotives being greater than the length of some of the blocks of the track.

Other objects and advantages will appear as the description of the invention progresses, and the novel features of the invention will be particularly pointed out in the appended claims.

Generally stated, the invention consists in providing an automatic cutout device in the supply wire for each ramp, whereby as soon 55 as current is drawn from one ramp the flow

of current to the ramp at the entrance to the preceding block will be immediately interrupted.

The invention further consists in the parts and in the arrangements and combinations 60 of parts, more fully set forth hereinafter.

In describing the invention in detail, reference is had to the accompanying drawing, wherein I have illustrated a preferred physical embodiment of my invention, and where- 65 in like characters of reference designate corresponding part throughout the several views, and in which:

The figure is a diagrammatic view of a train and a trackway therefor, and shows 70 the parts of an automatic train control system embodying the invention, both the parts which are associated with the train and the parts which are associated with the trackway. 75

Referring to the accompanying drawing, one rail of the trackway is electrically continuous, the separate rail sections thereof being bonded together; and the other rail 2 is divided into electrically isolated blocks 80 A, B, C, and D, as by insulating joints 3. The blocks may be of any suitable length required to obtain the desired spacing of the trains. At the entrance to each block a ramp R is supported in any suitable manner ad- 85 jacent to the track, but is insulated from said track. The current for the circuits of the system along the trackway is supplied from an alternating current line comprising wires 4 and 5, which are supplied with alter- 90 nating current from a suitable source, as a generator 6.

The parts associated with each block are the same, and the parts and electrical conductors for said parts associated with the blocks C and D will be given the same reference characters as the corresponding parts and conductors associated with the block A, with the distinctive exponents 1 and 2 added thereto. The normal direction of 100 traffic is indicated by the arrow X.

Adjacent to the exit end of each block is a track transformer 7, the primary of which is connected to the line wires 4 and 5, and the secondary of which is connected 105 by conductors 8 and 9 across the track rails 1 and 2 near the exit end of the corresponding block. Located at the entrance end of each block is a track relay 10, which is connected across the track rails 1 and 2 by con- 110

ductors 11 and 12, and which is provided with two armatures 13 and 14 represented according to the well known convention. A transformer 15 is provided for supplying energy to the ramps R in a way suitable for controlling the movement of the trains; and one terminal of the secondary of this transformer 15 is connected by conductors 16 and 8 to the track rail 1, said secondary 10 being provided with two taps 17 and 18 by means of which suitable voltages necessary for the proper operation of the automatic train control system may be obtained. The circuit breaking or interrupting device is 15 shown in the drawing as comprising a relay 19 having an armature 20; and for the purpose for which this relay is used, said relay is preferably constructed so as to be quick acting and its armature and co-operating 20 contacts are designed to interrupt comparatively large currents without injury.

The conductors and electrical connections between the different operative parts of the automatic train control system which are 25 located along the trackway will not be described in detail since these electrical connections and the different operating circuits will be fully set forth hereinafter in the description of the operation.

30 In the diagrammatic illustration shown in the accompanying drawings, the train comprises two pairs of wheels 21—21, 23—23 connected by their corresponding axles 22 and 24; and these pairs of wheels and axles 35 are connected by a bar 25 which represents the frame or body of the cars or locomotives constituting the train. The wheels and axles shown may be assumed to represent those of different motor cars or locomotives, 40 each of which is provided with automatic train control apparatus. The train control apparatus associated with each motor car or locomotive is constructed the same and a description of one will suffice for all. A bracket 26 of insulating material is suitably supported on each motor car or locomotive, being shown as mounted upon one of the journal boxes or axles; and supported on the bracket 26 is a vertically movable plunger or 50 shoe 27, which is pressed downwardly by a spring 28.

The shoes 27 are arranged in the same plane as the ramps R, so that as the train passes along the track said shoes will engage 55 said ramps. The shoes are designed to make electrical contact with the ramps R, and also to be moved in a way to actuate a circuit controlling device and interrupt a normally closed circuit on the train. To perform the latter functions, the shoe is shown provided 60 with a button 29 of insulating material, which is arranged to engage the underside of a contact spring 30 and lift said contact spring out of contact with a contact member 31 whenever the shoe 27 is raised.

The automatic control of the train is obtained by the operation of a suitable train control apparatus which is designed generally in the diagrammatic illustration by the reference character K. This device K may 70 be of any construction, and since it forms no part of the present invention, and since various devices well known in the art possess its necessary functions, the detail construction of this device K will not be herein described. The device K may be used to apply the brakes on the train instantaneously upon its operation or after a certain interval; and the operation of the device K may be made dependent in any suitable 80 way upon the speed of the train alone or on the speed and the distance between the train and the point of danger. The device K is illustrated as constructed so as to be set into operation when the energy which is normally supplied to it is cut off, and the device K is restored to its normal or idle condition when reenergized. The deenergization and reenergization of the device K is controlled by the armature 34 of a control relay 90 32 carried by the train, and when said control relay 32 is energized and its armature 34 is raised, the device K is energized from a suitable source of current, carried on the train, as a battery 35, according to the following circuit:

Circuit Number One.

Battery 35, conductor 36, device K, conductor 37, armature 34 of the control relay 100 32 in its upper position, and conductor 38 back to the battery 35.

When the shoe 27 is in its lower position the control relay 32 is normally supplied with current from a local battery 39 carried 105 by the train according to the following circuit:

Circuit Number Two.

From the battery 39, conductor 40, relay 110 32, conductors 41 and 42, armature 33 of the relay 32 in its upper position, conductor 43, contact spring 30, contact member 31, and conductors 44 and 45 back to the battery 39.

The control relay 32 is also controlled 115 by an alternating current pickup relay 46 having an armature 47; and when said pickup relay 46 is energized and its armature 47 is in its upper position, the control relay is energized according to the following 120 circuit:

Circuit Number Three.

From the battery 39, conductor 40, control relay 32, conductors 41 and 50, armature 47 of the pickup relay 46 in its upper position, and conductors 51 and 45 back to the battery 39.

The pickup relay 46 is connected by conductors 48 and 49 to the secondary of a 130

- transformer T carried on the train, and one terminal of the primary of said transformer T is connected by a conductor 52 to the bar 25 which represents the body or frame of 5 the train, and the other terminal of the primary of the transformer T is connected by a conductor 53 to the shoe 27. The conductors 53 of the different transformers T on the train are connected to a continuous 10 conductor or bus 54, which runs the entire length of the train and forms an electrical connection between the train control apparatus on the different motor cars or locomotives.
- 15 Operation: The general operation of the system herein disclosed is the same as that described in my prior application Serial No. 38,132, filed July 6, 1915, and to illustrate the features of the present invention, 20 this operation will be only briefly explained. The cutout relays 19 will be at first assumed to be in their normal de-energized condition and then their utility pointed out.
- 25 For the first case to be considered, assume that the train is about to enter the block B, and that neither the block B nor C is occupied. Under these conditions the track relays 10 and 10¹ of the blocks B and C respectively will be energized from the corresponding track transformer 7¹ and 7², as will be clearly understood by those skilled in the art of railway signaling. Since the 30 track relay 10 is energized and its armature 13 is in its upper position, a high difference of potential exists between the ramp R and the track rail 1 according to the following circuit:

Circuit Number Four.

40 From the ramp R, conductor 56, armature 13 in its upper position, conductor 57, cutout relay 19, conductor 58, high voltage tap 17 of the transformer 15 and conductors 16 45 and 8 to the track rail 1. When the first shoe 27 on the train engages the ramp R it breaks the normally closed circuit number two to the control relay by lifting the contact spring 30, and simultaneously makes electrical contact with the ramp R so that current is supplied to the primary of the transformer T from the transformer 15 according to the following circuit:

Circuit Number Five.

55 From the high voltage tap 17 of the transformer 15, conductor 58, cutout relay 19, conductor 57, armature 13 of the track relay 10 in its upper position, conductor 56, ramp R, shoe 27, conductor 53, primary of the transformer T, conductor 52, frame of the train 25, through the wheels and axles to the track rail 1, and thence by conductors 8 and 16 back to the other terminal of 60 the secondary of the transformer 15.

The current flowing in the primary of the transformer T induces a current in the secondary of said transformer which flows through the pickup relay 46 through the conductors 48 and 49, energizes said pickup 70 relay and causes its armature 47 to be raised and complete the pickup circuit number three for the control relay 32. In this way, at the same time that the normally closed circuit number two for energizing the control relay 32 is broken by raising the shoe 27, another circuit for energizing said control relay 32 is established; and, consequently, the armatures of said control relay are maintained in their upper position. 80

When the first wheels and axle of the train leave the block A and enter the block B, the track relay 10 will be deenergized, as will be clearly understood by those skilled in the art of railway signaling, and the armature 13 of said track relay will drop and interrupt the circuit number four. Since the block C is assumed to be unoccupied its track relay 10¹ is energized and a low difference of potential will be created between the ramp R and the track rail 1 according to the following circuit:

Circuit Number Six.

From the ramp R, conductor 56, armature 13 of the track relay 10 in its lower position, conductor 59, armature 20¹ of the cutout relay 19¹ in its lower position, conductor 60¹, armature 14¹ of the track relay 10¹ in its upper position, conductor 61¹, low voltage tap 18¹ of the transformer 15¹, and thence by conductors 16¹ and 8¹ back to the track rail 1. 95

The relay 46 is so designed that when its armature 47 is raised a low difference of potential between a ramp and a track rail is sufficient to hold said armature 47 in its raised position; but said low difference of potential is not sufficient to cause said armature to be raised from its lower position. In other words, high voltage is necessary to cause the armature 47 of the relay 46 to pick up, whereas a low voltage is sufficient to hold up said armature 47. This characteristic of the relay 46 may be obtained in different ways, as will be appreciated by those skilled in the art, and a detail description of the construction of the relay 46 is deemed unnecessary. 105 110 115

From the foregoing it can be seen that 120 when neither the blocks B nor C are occupied, and a train approaches the ramp R, the control relay 32, if energized, will remain energized, and if deenergized, will be reenergized; and subsequently, when the 125 train enters the block B, the control relay 32 will remain energized and prevent the operation of the control device K.

For the next case to be considered, assume that the block B is not occupied, but 130

that the block C is occupied by a train, and that the train is about to enter the block B. Under these conditions the track relay 10 of the block B is energized, and a high difference of potential exists between the ramp R and the track rail 1, according to the circuit number four, in the same way as hereinbefore described, while all of the wheels of the train remain on the block A. When 10 the train enters the block B and the track relay 10 is deenergized, no difference of potential will exist between the ramp R and the track rail, since the armature 14¹ is in its lower position and interrupts the circuit 15 number six because the block section C is assumed to be occupied. When no difference of potential exists between the ramp R and the track rail the armature 47 of the pickup relay 46 drops and interrupts the 20 pickup circuit number three for the control relay 32; and since the shoe 27 is in its raised position, the normally closed circuit number two for the control relay 32 is interrupted. Consequently, the armatures 33 25 and 34 of the control relay 32 drop; and the armature 33 opens a break in the normally closed circuit number two for said control relay, so that after the contact spring 30 has reestablished contact with the contact 30 member 31, the control relay 32 will not be reenergized, since the normally closed circuit number two will nevertheless be incomplete. In other words, whenever the control relay 32 is deenergized and its armature 33 drops, said control relay will remain deenergized until the relay 46 picks up and closes the pickup circuit number three for said control relay 32. The dropping of the armature 34 interrupts the supply 40 of current to the device K and causes said device K to be set into operation to control the train under conditions where it should proceed cautiously and be prepared to stop at the end of the block B.

45 From the foregoing, it can be seen that when the block C is occupied the train control device K is set into operation when the train enters the block B. With this general description of the operation of the 50 parts of the system located along the trackway, which description of the operation will be found fully amplified in said application Serial No. 38,132 hereinbefore referred to, the particular arrangement of devices and circuits embodying this invention can be pointed out more clearly.

Assume that the train includes two or 55 more motor cars or locomotives, each of which is provided with a contact shoe 27, the control relay 32, the pickup relay 46 and the associated electrical devices and connections; and further assume that said train is long enough to span the distance between two successive ramps, so that the

contact shoes of two different motor cars or 65 locomotives are in contact with two ramps at the same time, the condition being the same as that shown in the drawing. Disregarding the cutout relays 19 and their action, under the condition assumed, it can 70 be seen that part of the secondary of the transformer 15¹ is shortcircuited through a path of comparatively low resistance according to a circuit which may be traced as follows: 75

Circuit Number Seven.

From the ramp R, conductor 56, armature 13 of the track relay 10 in its lower position, conductor 59, armature 20¹, assumed to be 80 in its lower position, conductor 60¹, armature 14¹ of the track relay 10¹ in its upper position, conductor 61¹, low voltage tap 18¹ of the secondary of the transformer 15¹, high voltage tap 17¹, conductor 58¹, cutout relay 85 19¹, conductor 57¹, armature 13¹, of the track relay 10¹ in its upper position, conductor 56¹, ramp R¹, contact shoe 27 of the forward motor car, conductor 53, bus 54, conductor 53, shoe 27 of the rear motor car back to 90 the ramp R. This short circuit of part of the secondary of the transformer 15¹ not only causes improper and undue current to flow through said secondary, but also prevents the energization of the pickup relays 95 46, even though traffic conditions are such that said relays should be energized. However, in tracing the above circuit number seven the action of the cutout relays 19 was disregarded; and it can be seen that as soon 100 as current flows to the ramp R¹ it passes through the cutout relay 19¹ and raises its armature 20¹ to interrupt the connection between the transformer 15¹ and the preceding ramp R. In short, the action of the cutout 105 relays 19 is such that as soon as current is being drawn from one ramp the supply of current to the preceding ramp is interrupted. Consequently, the cutout relays 19 prevent any improper or excessive flow of current 110 when a train including two or more motor cars or locomotives is longer than the distance between two succeeding ramps. From a consideration of the circuits shown and hereinbefore traced it can be seen that, in 115 effect, there are two partial circuits associated with each ramp, that the cutout relay is included in one of said partial circuits at each ramp and that the armature of said cutout relay is included in the other partial 120 circuit of the preceding ramp.

The electrically operated devices along the trackway are shown as arranged and designed to be operated by alternating current alone, but it is to be understood that by a 125 simple modification, which will be apparent to those skilled in the art of railway signaling, these devices may be so constructed, that

direct current may be used as the operating medium. Also, although only two motor cars or locomotives are represented in the drawing, any number of motor cars or locomotives may be used and any number of contact shoes may be employed without affecting the operation of the system. Various other changes in the particular arrangement of circuits and parts shown and described may be made without departing from the invention or the particular physical embodiment thereof.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In a system for automatically controlling railway trains, in combination: a plurality of vehicles each carrying contact devices; an automatic train control apparatus carried by each of said vehicles; a controlling circuit for each train control apparatus including the contact device and the frame of the corresponding vehicle; a continuous conductor connecting said controlling circuits of all of said vehicles; insulated contact rails located along the trackway for said vehicles and adapted to coöperate with said contact devices; two partial circuits associated with each contact rail for creating a difference of potential between said contact rail and the track rails; and a means associated with each contact rail and operated by the flow of current in one of said partial circuits of that contact rail for interrupting the other partial circuit of the preceding contact rail.
2. In a system for automatically controlling railway trains, in combination; insulated contact rails located along the trackway for the vehicles; a partial circuit associated with each contact rail for creating a difference of potential between said contact rail and the track rails; a second partial circuit associated with each contact rail for creating a different difference of potential between said contact rail and the track rails; and means associated with each of said contact rails and operated by the flow of current in said first-mentioned partial circuit for interrupting said second partial circuit of the preceding contact rail.
3. In a system for automatically controlling railway trains, in combination: a trackway divided into electrically isolated blocks; an insulated ramp at the entrance to each block; a source of current and a track relay

constituting a normally closed track circuit; sources of high and low voltage associated with each ramp; a partial circuit associated with each ramp and closed when the track relay of the corresponding block is energized for connecting said source of high voltage across said ramp and the track rails; a second partial circuit associated with each ramp and closed when the track relay of the corresponding block is energized and the track relay of the preceding block is deenergized, said second partial circuit connecting said source of low voltage across the preceding ramp and the track rails; and means operated by the flow of current in said first-mentioned partial circuit for interrupting said second-mentioned partial circuit.

4. In a system for automatically controlling railway trains, in combination: insulated contact rails located along the trackway for said vehicles; sources of high and low voltage associated with each contact rail; two partial circuits each including said contact rail, the track rails and one of said sources; a translating device included in one of said partial circuits; and normally closed coöperating contacts opened when said translating device is energized and included in said other partial circuit.

5. In a system for automatically controlling railway trains in combination: insulated contact rails located along the trackway for said vehicles; sources of high and low voltage associated with each contact rail; means responsive to the presence of a vehicle on the adjacent trackway for controlling the connection between said sources and the corresponding contact rails; a line wire arranged to connect one of said sources at times to the preceding contact rail; and means operated by the flow of current to any one of said contact rails for interrupting the line wire leading to the preceding contact rail.

6. In an automatic train control system, a vehicle and a track therefor, impulse devices located at intervals along the track and adapted to communicate electric impulses to a passing vehicle, means rendered effective by the communication of impulses from any one of said impulse devices for rendering the impulse device next in the rear thereof inactive.

7. In a system for automatically controlling railway trains having a number of vehicles, impulse devices located at intervals along the track for the vehicles and adapted to transmit electric impulses to each passing vehicle of a train, automatic train control apparatus on each vehicle governed by the transmitted impulses, a continuous conductor on the train for transmitting the impulses from one vehicle to the others, and

- means associated with each impulse device on the track and rendered active by the transmission of current therefrom to a vehicle for rendering the impulse device next in the rear thereof inactive.
8. In an automatic train control system, a train including a number of vehicles and a track therefor, means comprising impulse devices along the track and coöperating elements on each vehicle for transmitting current impulses from the track to the vehicle at different control points, automatic train control apparatus on each vehicle governed by said current impulses, a conductor for transmitting the current impulses from any vehicle of the train to the others, and means for preventing an electrical connection existing between any two successive impulse devices along the track.
9. In an automatic train control system, a track divided into track circuit sections, impulse devices located at intervals along the track and adapted to communicate electrical impulses to a passing vehicle, partial circuits for supplying current to said impulse devices, and means for temporarily interrupting the partial circuit associated with each impulse device as the vehicle reaches the next impulse device in advance.
10. In an automatic train control system, impulse devices located at intervals along the track and adapted to coöperate with means on a passing vehicle and transmit controlling impulses thereto, a control circuit associated with each impulse device, and

electro-responsive means included in the control circuit for each impulse device for governing the control circuit of the impulse device next in the rear.

11. In an automatic train control system for railroads having tracks divided into blocks each provided with a normally closed track circuit, impulse devices located at intervals along the track, a control circuit for each impulse device governed by some of said track circuits, and electro-responsive means included in the control circuit for each impulse device for governing the control circuit associated with the impulse device next in the rear. 50

12. In an automatic train control system for railroads having tracks divided into blocks each provided with a normally closed track circuit, an impulse device at the entrance to each block controlled by the track circuit of the block next in advance of the corresponding block, a train including a number of vehicles each equipped with means for coöperating with said impulse devices, and each having train control apparatus thereon, said train being longer than some of said blocks and having the train control apparatus on the several vehicles inter-connected for simultaneous operation, and means associated with each impulse device of such short blocks and influenced by its coöperation with said vehicle carried means for rendering the impulse device next in the rear inactive. 65

WINTHROP K. HOWE.
